DYEING PREPARATION AND ITS CONVER-
SION TO DYESTUFFSArthur Zitscher and Wilhelm Seidenfaden, Offen-
bach - on - the - Main, Germany, assignors to
General Aniline Works, Inc., New York, N. Y.,
a corporation of DelawareNo Drawing. Application December 4, 1931,
Serial No. 579,115. In Germany December 9,
1930

7 Claims. (Cl. 8—6)

Our present invention relates to new dyeing preparations and their conversion to dyestuffs.

These dyeing preparations contain an aryl-anti-diazo-sulfonate corresponding to the probable general formula:

10 wherein X and Y mean alkyl, alkoxy or halogen, and a combining component containing a hydroxy or an O-alkali-metal group whereof the adjacent position is capable of attaching an aryl-azo-group.

15 The anti-azo-sulfonates we use in our present invention are described and claimed in our co-pending U. S. Patent Number 1,909,851, filed December 4, 1931 and issued on May 16, 1933 in the name of Arthur Zitscher and Wilhelm Seidenfaden.

20 As combining components of the aforesaid kind may be named: 2-hydroxy-naphthalene, its nuclear substitution products as, for instance, arylamino-hydroxy-naphthalenes, (2-hydroxy-naphthalene - 3 - carbonyl)-amino-aryls (as described in U. S. Patent No. 1,101,111 and U. S. Patent No. 1,140,747), (6-halogen- or arylamino-2 - hydroxy - naphthalene - 3 - carbonyl)-amino-aryls (see German Patent No. 396,519 and British Patent No. 330,349); derivatives of 1-hydroxy-naphthalene-4-carboxylic acid (see U. S. Patent No. 1,453,660) as for instance, 1-hydroxy-naphthalene-4-phenyl-ketone; compounds containing an acidic methylene-group capable of being combined with diazo-compounds as for instance pyrazolones and derivatives of β -keton-aldehyde for instance aceto-acetyl-amino-aryls and di-(aceto-acetyl-amino)-aryls (see U. S. Patents No. 1,594,864, No. 1,594,866, No. 1,594,867, No. 1,580,709, No. 1,634,090); dihydroxy-quinolines (see U. S. applications Serial No. 352,317 and No. 352,319, U. S. Patent No. 1,820,039; British Patent No. 332,940); (2-hydroxy-carbazole-3-carbonyl) - amino - aryls, (2-hydroxy - benzocarbazole-3-carbonyl) - amino - aryls, (2-hydroxy-anthracene-3-carbonyl) - amino - aryls.

25 These dyeing preparations yield when applied in an alkaline medium to fibers, by steaming only, insoluble azo-dyestuffs on the fibers.

30 Such applying to the fibers consists in dyeing according to the one-bath-method or in printing. The dye-bath or the printing paste or also the pulverulent dyeing preparations themselves are advantageously mixed with dyeing expedients having wetting, emulsifying or dissolving proper-

ties or also with the additional agents customary in using nitrosamine-printing-colors, as, for instance, chromate.

35 In order to further illustrate our invention the following examples are given, the parts being by weight and all temperatures in centigrade degrees. But it may be understood that our invention is not limited to the particular products or reaction conditions mentioned therein.

Example 1

A printing paste which contains
19 parts of the sodium salt of 4-acetylamino-
2,5-dichloro-benzene-1-anti-azo-sulfonic acid
15 parts of (2-hydroxy-naphthalene-3-car-
bonyl-amino)-benzene
20 parts of caustic soda lye of 34° Bé.
20 parts of thiodiglycol
426 parts of water
500 parts of neutral starch tragacanth-thick-
ening is printed on textile materials. The goods
thus printed are steamed for 7 minutes in the
Mather-Platt, passed through an acid bath,
soaped and rinsed.

40 In this manner a clear dark garnet print is
obtained.

Example 2

A printing paste which contains
22.3 parts of the sodium salt of 4-benzoylamino-
2-methoxy-5-chloro-benzene-1-anti-azo-sulfonic
acid
15.0 parts of (2'-hydroxy-naphthalene-3'-car-
bonyl-amino)-benzene
20.0 parts of caustic soda lye of 34° Bé.
50.0 parts of thiodiglycol
392.0 parts of water
500.0 parts of neutral starch tragacanth-thick-
ening is printed on textile materials. The goods
thus printed are slightly dried, passed through
hot drying-cylinders, steamed for 10 minutes in
the Mather-Platt, rinsed at the hot, soaped and
rinsed again.

45 In this manner a violet print is obtained.

Example 3

A printing paste containing
28.2 parts of the sodium salt of 4-benzoyl-
amino-2-methyl-5-methoxy-benzene-1-anti-azo-
sulfonic acid
20.0 parts of (2'-hydroxy-naphthalene-3'-car-
bonyl-amino)-benzene
30.0 parts of caustic soda lye of 34° Bé.
30.0 parts of thiodiglycol
372.0 parts of water
500.0 parts of neutral starch tragacanth-thick-
ening

65

70

75

80

85

90

95

100

105

110

20.0 parts of sodium chromate solution 1:4 is printed on textile materials, somewhat dried, steamed for 10 minutes in the Mather-Platt, soaped and rinsed.

5 In this manner a violet shade is obtained.

Example 4

A printing paste which contains

40.0 parts of a mixture, prepared by milling together 52.4% of the potassium salt of 4-benzoyl-amino-2,5-dimethoxy-benzene-1-anti-azosulfonic acid, 37.6% of 1-(2'-hydroxy-naphthalene-3'-carbonyl-amino)-2-methyl-benzene, 10.0% of caustic soda,

15 5.0 parts of caustic soda lye of 34° Bé.

20.0 parts of thioglycol

415.0 parts of water

500.0 parts of neutral starch tragacanth-thickening

20 20.0 parts of sodium chromate solution 1:4 is printed on cotton materials. The goods thus printed are dried, steamed for 15 minutes in the Mather-Platt, rinsed, soaped and washed.

A clear reddish blue print is obtained.

Example 5

25 parts of 1-(2'-hydroxy-naphthalene-3'-carbonyl-amino)-2-methyl-4-methoxy-benzene are milled to a homogeneous mixture with 45 parts of the sodium salt of 4-benzoyl-amino-2-chloro-5-methoxy-benzene-1-anti-azo-sulfonic acid of 80%.

This mixture is worked up to a printing paste with

35 30 parts of caustic soda lye of 34° Bé.

30 parts of thioglycol

350 parts of water

500 parts of neutral starch tragacanth-thickening

40 20 parts of sodium chromate solution 1:4 which is printed on cotton goods in the usual manner. A red-violet print is obtained.

Example 6

45 15.0 parts of 1-(2'-hydroxy-naphthalene-3'-carbonyl-amino)-2-methoxy-benzene, 4.75 parts of 4,4'-bis-(aceto-acetyl-amino)-3,3'-dimethyl-diphenyl, 28.0 parts of the sodium salt of 4-benzoyl-amino-2,5-dimethoxy-1-anti-azo-sulfonic acid of 87% are milled to a homogeneous mixture which is worked up to a printing paste with

25 parts of caustic soda lye of 34° Bé.

20 parts of thioglycol

55 387 parts of water

500 parts of neutral starch tragacanth-thickening

60 20 parts of sodium chromate solution 1:4. By printing this paste in the usual manner on cotton materials a full olive-brown print is obtained.

Example 7

Bleached cotton piece-goods are impregnated with the following solution:

65 15 parts of (2'-hydroxy-naphthalene-3'-carbonyl-amino)-benzene

75 parts of the sodium salt of 2,5-dimethoxy-4-(4'-methyl-benzene-sulfonyl-amino)-benzene-

70 1-anti-azo-sulfonic acid

30 parts of tragacanth-mucilage 65:1000

33 parts of caustic soda lye of 34° Bé.

20 parts of Turkey red oil

815 parts of water

75 20 parts of sodium chromate solution 1:4.

Then the goods are dried, steamed for 5-10 minutes in the Mather-Platt, hot rinsed and soaped shortly.

In this manner a reddish violet self-dyeing is obtained.

In the following table we have inserted the shades of a series of further dyeings or prints, produced in an analogous manner:

Since an object of the present invention is to produce dyestuffs of good fastness properties which dyestuffs are insoluble in water and alkalies, it is to be understood that the aromatic nuclei of the general formulae appearing in the appended claims contain no substituents as are known to render organic compounds soluble in water or alkalies and to tend to depreciate the fastness of the dyestuffs to alkalies. Substituents of this kind are the sulfonic acid, the carboxylic acid and the hydroxy group.

We claim:

1. As new compositions of matter the dyeing preparations comprising an aryl-anti-diazo sulfonate corresponding to the probable general formula:

wherein X and Y mean alkyl, alkoxy or halogen, and a combining component containing a hydroxy- or an O-alkali-metal-group whereof the adjacent position is capable of attaching an aryl-azo-group, which dyeing preparations yield in the presence of caustic alkali by steaming azo-dyestuffs insoluble in water and alkali.

2. As new compositions of matter the dyeing preparations comprising an aryl-anti-diazo sulfonate corresponding to the probable general formula

wherein X and Y mean alkyl, alkoxy or halogen and R a radical of the aromatic homocyclic series, and an aromatic isocyclic compound which contains a hydroxy or an O-alkali-metal-group, a free ortho-position relative to the said group capable of attaching an aryl-azo-group and which may contain as substituents aroylamino, aroyl, halogen, arylaminocarbonyl, which dyeing preparations yield in the presence of caustic alkali by steaming azo-dyestuffs insoluble in water and alkali.

3. As new compositions of matter the dyeing preparations comprising an aryl-anti-diazo sulfonate corresponding to the probable general formula:

wherein the benzene nucleus I may contain alkyl, alkoxy or halogen and Y means alkyl, alkoxy or halogen, and an aromatic isocyclic compound

which contains a hydroxy- or an O-alkali-metal-group, a free ortho-position relative to the said group capable of attaching an aryl-azo-group and which may contain as substituents aroylamino, aroyl, halogen, arylaminocarbonyl, which dyeing preparations yield in the presence of caustic alkali by steaming azo-dyestuffs insoluble in water and alkali.

4. As new compositions of matter the dyeing preparations comprising an aryl-anti-diazo sulfonate corresponding to the probable general formula:

wherein the benzene nucleus I may contain alkyl, alkoxy, or halogen and Y means alkyl, alkoxy or halogen, and a (2-hydroxy-naphthalene-3-carbonyl)-amino-aryl of the formula:

wherein Z means a radical of the benzene or naphthalene series, which dyeing preparations yield in the presence of caustic alkali by steaming azo-dyestuffs insoluble in water and alkali.

5. As a new composition of matter the dyeing preparation consisting of

36.0 parts of the sodium salt of 4-benzoylamino-2-chloro-5-methoxy-benzene-1-anti-diazo sulfonic acid

25.0 parts of 1-(2'-hydroxyl-naphthalene-3'-carbonyl)-amino-2-methyl-4-methoxy-benzene, which dyeing preparation yields when brought onto fibers by steaming red-violet dyeings and printings.

6. As a new composition of matter the dyeing preparation consisting of

52.4 parts of the sodium salt of 4-benzoylamino-2,5-dimethoxy-benzene-1-anti-diazo-sulfonic acid

37.6 parts of 1-(2'-hydroxy-naphthalene-3'-carbonyl)-2-methyl-benzene

10.0 parts of sodium hydroxide, which dyeing preparation yields when brought onto fibers by steaming reddish blue dyeings and printings.

7. As a new composition of matter the dyeing preparation consisting of

57.5 parts of the sodium salt of 4-benzoyl-amino-2,5-diethoxy-benzene-1-anti-diazo-sulfonic acid.

42.5 parts of the disodium salt of (2'-hydroxy-naphthalene-3'-carbonyl)-amino-benzene, which dyeing preparation yields when brought onto fibers by steaming blue dyeings and printings.

ARTHUR ZITSCHER.
WILHELM SEIDENFADEN.
